UNITED STATES PATENT OFFICE.

SAMUEL MAROGER, OF NIMES, FRANCE.

ROTARY PUMP FOR LIQUIDS OR GASES.

Application filed October 27, 1924. Serial No. 746,106.

To all whom it may concern:

Be it known that I, SAMUEL MAROGER, a citizen of the Republic of France, residing at 26 Rue Dhuoda, Nimes, Gard, France, have invented new and useful Improvements in Rotary Pumps for Liquids or Gases, of which the following is a specification.

Rotary pumps, of the screw type usually comprise a screw rotating in a cylinder and

- 10 a special device (star or toothed wheel) which prevents the liquid which fills the pump from taking part in the rotary movement of the screw, so that the liquid moves in accordance with the generatrices of the 15 cylinder which forms the body of the pump and it remains constantly imprisoned between the threads of the screw.

Such an arrangement is subject to the drawback that it complicates the internal 20 mechanism of the apparatus owing to the fact that special means must be provided to prevent the liquid from participating in the movement of the screw.

This invention relates to a pump of the 25 type referred to which does not comprise any special means for the purpose mentioned, apart from the body of the pump itself and the screw, the screw being arranged in such a manner that the helicoidal entrainment of 30 the fluid (liquid or gas) cannot take place. The device presents the further advantages, owing to the uses to which it can be put, of enabling large outputs to be obtained as well as of being capable of running at approximately the same speeds as the motor 35 to which the pump is coupled, the same arrangement being applicable for the purpose of obtaining high vacua or pressures.

The invention consists in mounting, in the 40 body of the pump, a drum of smaller diameter which constitutes the body of the driving screw and in placing this drum eccentrically relative to the pump body in such a manner that they are tangential to each 45 other, the said drum having a helicoidal groove in which is fitted a helix of corresponding pitch, but of the same diameter as the pump body, the helix being fitted in its groove with a certain amount of clearance 50 in order to enable it to move therein and to take up easily any wear which may arise.

In order to avoid leakage and to ensure 55 tightness of the pump, it is necessary that the thread of the helix shall make a number of revolutions or fractions of revolutions such that the same thread touches the pump-

body at least twice. In the case of a pump having a single thread, two revolutions are therefore necessary and the pump-body must be made sufficiently long. If, however, two 60 threads are provided, one and one half revolutions will be sufficient to ensure tightness, and by this means the length of the pump body necessary for a given output can be diminished.

The invention contemplates the formation of the body of the screw of a series of discs, placed side by side, and mounted upon the same shaft, which is eccentric to the pump-body, these discs having straight grooves of 70 suitable inclination and corresponding to that of the thread of the screw which it is desired to obtain, and also the mounting of straight blades in these grooves in such a 75 manner that they can move therein independently of each other, the entire device, while presenting the general aspect of a screw and offering the advantage that its manufacture and erection are simple, while its operation is consistent.

In the drawing, Fig. 1 is a transverse section of a rotary pump constructed according to the present invention.

Figs. 2 and 3 are detail views showing, respectively, one of the discs shown in Fig. 85 1 and one of the blades intended to be mounted in this disc.

In the examples shown in Figs. 1 to 3, the pump-body 1 is provided at its extremities with admission and discharge nozzles 2 and 3 and has bearings 4 for the reception of the shaft of the rotary member of the pump, these bearings being formed eccentrically relative to the pump-body 1. The rotary member comprises a series of disks 10 of smaller diameter than the interior of the body of the pump and placed side by side on the shaft 6 and, owing to the eccentricity of the shaft 6, which can rotate in the bearings 4, the disks 10 are tangent to the bore 90 of the body of the pump only along one of their generatrices. A thrust-bearing is formed at one of the extremities of the shaft 6, while the other extremity rotates in a stuffing box 7 which ensures a fluid tight 100 105 fit.

Upon the disks 10 there are formed obliquely straight grooves 12, the sequence of which represents substantially the aspect of a helicoidal groove formed of broken lines; and, in the case of two threads, these grooves 110 will be disposed inversely relative to the two extremities of a diameter of each of the

disks, in such a manner that each of the extremities of the grooves of one of them coincides with the extremity of a groove of the adjacent disk. The blades 11 can be mounted in the grooves 12 and can move in the latter, the face 13 of each of said blades being formed in such a manner that it can bear exactly upon the bore of the body of the pump. The blades are constantly pressed 10 against the bore of the body of the pump by centrifugal force, so that any wear is automatically compensated. The shaft 6 of the drum, being driven by the motor, the disks 10 comprising the rotary member and 15 the blades 11 carried thereby are caused to rotate. The fluid (gas or liquid) which fills the pump, cannot take part in the rotary movement of the helix formed by the blades 11 since there is no room for the passage of 20 such fluid at the line of tangency between the disks 10 and the body 1 of the pump, so that it can only follow the advancing movement of the helix. The result is that the fluid taken in at the admission nozzle 2 is 25 forced out through the discharge nozzle 3.

It is evident that certain modifications could be made in this arrangement of rotary pump or that other systems of mounting the screw could be devised without departing 30 from the spirit of the invention.

I claim:

1. A rotary pump comprising in combination a pump-body, a drum mounted eccentrically in said pump-body, said drum having 35 a helical groove, and a helix fitted in said

groove, said helix being made in sections for the purpose set forth.

2. A rotary pump comprising in combination a pump-body, a drum mounted eccentrically in said body so as to contact therewith along one generatrix alone, said drum having a plurality of helicoidal grooves, and a helix formed in sections fitted in each of said grooves. 40

3. A rotary pump comprising in combination a pump-body, a plurality of discs mounted eccentrically in said body and contacting therewith along a generatrix, said discs having grooves, and blades fitted in said grooves and adapted to contact with the 50 inner wall of said pump body. 45

4. A rotary pump comprising in combination a pump-body, a plurality of discs mounted eccentrically in said body and contacting therewith along a generatrix, said 55 discs having straight grooves arranged obliquely, and blades fitted in said grooves and contacting with the inner wall of said pump body.

5. A rotary pump comprising in combination a pump-body, a shaft mounted eccentrically in said pump-body, a plurality of discs mounted concentrically upon said shaft and of such diameter as to contact with said pump-body along one generatrix only, said 60 discs having straight grooves arranged in such relative formation as to form substantially a helicoidal line, and blades fitted in said grooves. 65

SAMUEL MAROGER.
